UNITED STATES PATENT OFFICE.

BASIL R. CRAMPTON, OF DETROIT, MICHIGAN, ASSIGNOR TO CRAMPTON AUTOMATIC PRESSURE FASTENER COMPANY, OF DETROIT, MICHIGAN, A CORPORATION OF MICHIGAN.

LATCH-SPRING FASTENER.

1,157,086.

Specification of Letters Patent. Patented Oct. 19, 1915.

Application filed July 31, 1915. Serial No. 42,903.

To all whom it may concern:

Be it known that I, BASIL R. CRAMPTON, a citizen of the United States, residing at Detroit, county of Wayne, State of Michigan, have invented a certain new and useful Improvement in Latch-Spring Fasteners, and declare the following to be a full, clear, and exact description of the same, such as will enable others skilled in the art to which it pertains to make and use the same, reference being had to the accompanying drawings, which form a part of this specification.

This invention relates to improvements in latches especially to improvements in that type of latch which operates upon the toggle-arm principle.

The improvements embodied in the present application relate to a new way of mounting the spring upon the base plate whereby the spring has considerable freedom of action, thereby very materially increasing its life.

In the drawings, Figure 1, is a longitudinal section through the spring and base plate showing the toggle arms in elevation. Fig. 2, is a longitudinal section of the blank from which the base plate is stamped, showing how the center of the blank is raised up to form a support for the spring. Fig. 3, is a plan view of the base plate.

The arrangement of the toggle parts is shown in Fig. 1. These comprise a pair of toggle arms held together in the center by a button *a* and yieldingly prevented from approaching toward their dead center by reason of the pressure of the spring ends *b*. The shoulders *c* act as stops to prevent the toggle arms opening out farther than shown in Fig. 1. The ends of the springs *b* are curled over to form a bearing upon which the toggle arms turn, the toggle arms being notched to receive the bearing. This much of the invention is old.

The invention here sought to be secured is the means by which the spring *d* is secured to the base plate *e*. The base plate comprises a blank, as shown in Fig. 2. This blank is slotted at *f*, *f*; the metal between the slots is then pressed up, as shown by the dotted lines in Fig. 2, to form a boss *g*. Portions of the side of the boss are turned over to form retaining lugs *h*. The spring is passed through the slots *f*, *f* and the retaining lugs *h* are then pressed down over

the spring. This not only tends to retain the spring against longitudinal movement and lateral movement, but it also serves to slightly bow the spring in, so as to keep it out of contact with the member to which the base plate is secured.

If desired, the spring may be provided with a centrally located opening *i* and into this may be pressed a point *j* in the boss. This also serves to locate and position the spring with respect to the base plate. It, in connection with the lugs *f*, prevents the longitudinal shifting of the spring.

It has been found by actual tests that the life of a spring secured to a base plate in the manner described above is very materially lengthened. This is due to the fact that there is considerable freedom of action between the spring and the base plate, not only at the point where the spring first comes into contact with the base plate but all along those portions where the spring and the boss of the base plate are substantially parallel.

By securing the spring on the under side of the plate at the spring's center and holding it away from adjacent surfaces at the back of the spring, as by the boss for instance, the two portions of the spring on the sides of the fastening are free to vibrate from the center of the spring instead of at the zones where the spring legs have a parallel abutting relation with the base plate as would be the case where the spring is clamped or riveted to the top of the base plate and lies directly thereagainst. Hence when the toggle levers pass dead center and spread the legs of the U, some of the binding strains are taken at the center of the spring as well as at the zones where the legs are bent upwardly.

What I claim is:

1. In a latch, the combination of a pair of toggle arms, a U-like spring upon the free end of which the toggle arms are pivoted, and a base plate provided with a portion arranged to form a free space or chamber thereunder, the said U-like spring being fastened at its middle to the under side of said portion, and the said legs of the U-like spring curved upward at the ends of said portion, substantially as described.

2. In a latch, the combination of a pair of toggle arms, a U-like flat spring upon the ends of which the toggle arms are rotatably

mounted, a base provided with a pair of slots and a boss between the pair of slots, the said U-like spring passing through the slots and under the boss.

3. In a latch, the combination of a pair of toggle arms, a flat U-like spring upon whose ends the toggle arms are rotatably mounted, a base provided with a pair of slots and a boss raised between the slots, the said U-like 10 spring passing through the slots and under the boss, and means for helping retain the said U-like spring in a given position with respect to the base plate.

4. In a latch, the combination of a pair of 15 toggle arms, a U-like flat spring upon the ends of which the toggle arms are pivoted, a base plate provided with a pair of slots, and a boss raised between the slots, said U-like 20 spring passing through the slots and under the boss, the said metal forming the

base being struck out in lugs which are bent over to engage the sides of the spring under the boss.

5. In a latch, the combination of a pair of toggle arms, a flat U-like spring upon the 25 free ends of which the toggle arms are pivoted, a base plate provided with a pair of slots, and a boss raised between the slots, the said U-like spring passing through slots and under the boss, means for connecting 30 the sides of the spring with the said boss, said spring being provided with a central opening and the said boss being provided with a struck-in portion which engages in said opening to position the said spring with 35 respect to the base.

In testimony whereof, I sign this specification.

BASIL R. CRAMPTON.
